Attorney.

UNITED STATES PATENT OFFICE.

HARRY E. MAY, OF SEDALIA, MISSOURI, ASSIGNOR, BY DIRECT AND MESNE ASSIGNMENTS, OF TWO-THIRDS TO HOLMES HALL, OF SEDALIA, MISSOURI.

CARBURETER ATTACHMENT.

1,282,902.

Specification of Letters Patent. Patented Oct. 29, 1918.

Application filed September 19, 1917. Serial No. 192,048.

To all whom it may concern:

Be it known that I, HARRY E. MAY, a citizen of the United States, residing at the city of Sedalia, in the county of Pettis and State of Missouri, have invented certain new and useful Improvements in Carbureter Attachments, of which the following is a specification.

This invention is in the nature of a carbureter or an auxiliary carbureter or an adjunct to a carbureter. It is not necessarily to be attached to a carbureter, but will be so located relative to the gas inlet to an internal combustion engine as to give the best results or to be most conveniently attached. In the drawings it is shown connected to the intake manifold of such an engine.

This device serves the double purpose of forming a more highly explosive mixture and therefore one which produces more power and also of keeping the cylinders and other parts free of carbon.

In actual use it has been found to increase the mileage of a motor vehicle by thirty-five to forty per cent. from the same quantity of gasoline, or otherwise stated, it has thus been found to save about twenty-five to thirty per cent. of the gasoline for the same mileage.

In the accompanying drawings forming part of this specification, in which like numbers of reference denote like parts wherever they occur,

Figure 1 is a side elevation (partly in section) showing the relation of this device to associated parts of a motor vehicle;

Fig. 2 is a detail of a knob mounted upon the instrument board of a motor vehicle, by which knob this invention may be rendered active or inactive;

Fig. 3 is a side elevation of this device;

Fig. 4 is a view taken on the line 4—4 in Fig. 3 looking in the direction of the arrows;

Fig. 5 is a view taken on the line 5—5 in Fig. 1 looking in the direction of the arrows; and

Fig. 6 is a view taken on the line 6—6 in Fig. 1 looking in the direction of the arrows.

This device is mounted adjacent to the exhaust manifold 1 or exhaust pipe of an internal combustion engine, preferably by means like the threaded stud 2, and consists primarily of a member 3 containing a cham-

ber in which chamber is located a plunger 4 55 from one end of which projects an elongated stud 5. This stud extends through the passage 6 by which the said chamber communicates with a water pipe 7 which is threadedly connected with externally threaded collar 8. The inlet of water is shut off from pipe 7 by the said stud 5 when the said stud is in the position shown in Fig. 1, but when the said stud is retracted by the movement of plunger 4 in a direction away from pipe 65 7, water is allowed to flow through passage 6 and into the chamber within member 3. Due to the fact that stud 5 practically fills passage 6, the admission of water therethrough is in the form of a film covering the 70 surface of stud 5, which is quickly converted into steam by the inrush of hot air through the air-inlet 9, formed through the wall of the chamber 3 and located, as above stated, adjacent to the exhaust manifold 1 or some 75 similar hot part of the engine whereby the air is heated. The heat from the exhaust also passes through stud 2 directly to stud 5 and prepares the film of water for vaporization. The action of the pistons of the 80 engine relative to the intake manifold is well understood, the same exerting a drawing power through the said intake manifold whereby the said steam and hot air from air-inlet 9 are drawn through outlet 11 into the 85 intake manifold connection 10 and thence into the intake manifold and cylinders of the engine.

The mixture of too much air with the gasoline in the carbureter proper makes the 90 gas too thin and the engine will not operate properly; but the addition of steam and hot air to the gas after the gas has entered the intake manifold from the carbureter is found to be advantageous to the mixture 95 and to give more power and to effect a consequent saving in the consumption of gasoline, there being a better admixture of air and gasoline in the intake manifold than is possible in the carbureter proper. The great 100 heat entering through air-inlet 9 heats the steam and raises the gas that enters from the carbureter to the high temperature of the steam, which high temperature and the presence of steam contributes to the above stated 105 beneficial result. Moreover, the introduction of steam into the cylinders and other parts of the engine clears out all existing carbon,

and thereafter the continual admission of steam in the manner hereinbefore stated keeps the cylinders and all other parts with which it comes in contact free from carbon.

5 This alone tends to an increase in the power as well as economy in operation and repairs.

When the device is in the position shown in Fig. 1, air-inlet 9 is closed by plunger 4, as is also the outlet 11 and the water inlet 10 from pipe 7, and plunger 4 is caused to move to the right in Figs. 1 and 3 by the opening of the gasoline throttle. No means is shown in the drawings for controlling the rod 12, which is so connected by a rod 13 attached 15 to the lever 14 as to move plunger 4 either to the right or to the left in Figs. 1 and 3. Although not shown in the drawings, any suitable means may be used to operate rod 12, and such means will be preferably connected to both the foot throttle and the hand throttle, so as to be actuatable by either, which hand and foot throttles may be of any common or ordinary type not necessary to be shown. In case of the presence of intervening parts of any particular machine that make it impossible to use a rod 13, a flexible shaft may be substituted therefor, and either the said draft or rod 13 can be removably and adjustably attached in any 25 suitable manner in one of the holes 15 in the lever 14.

The lever 14 is pivoted at 16 in the slot 17 in lever 14 and is furthermore fulcrumed at 18 on forked bracket 19. Stud 20 extends 35 from rod 13 through one of the holes 15.

The advantage of controlling the degree of opening of inlet 9 and outlet 11 by movement of the gasoline throttle is that when the engine is throttled down it is undesirable 40 to have the advantages in the mixture in the intake manifold hereinbefore described; but when the throttle is open while the vehicle is running freely along the road or when the throttle is wide open because 45 of a hard pull, then it is desirable that the opening of the throttle shall simultaneously have moved plunger 4 to the right in Figs. 1 and 3 so as to give a larger passage through inlet 9 and outlet 11 and that there 50 should at such time be a larger part of stud 5 exposed with its film of water, whereby a larger amount of steam will be formed.

Water pipe 7 may communicate with the water jacket of the engine or with the radiator, or with any other suitable water supply. Heated water is preferable as it more readily can be converted into steam, but on account of the same emerging into the chamber within member 3 only in the form of a 55 film covering stud 5, the same will in any event be quickly vaporized by the hot air that enters through inlet 9 and the heat of stud 2.

When the engine is being started and before 60 the steam becomes warm it is undesirable

that the steam or air from this device shall enter the intake manifold and for that reason a valve 21 is provided in coupling 22 between outlet 11 and the intake manifold connection 10 (as shown in Figs. 1 and 6). The said valve 21 is pivoted in the walls of coupling 22 and moved to open or closed position by pulling or pushing on knob 24 supported by bracket 25, which bracket is attached by screws 26 to instrument board 27 of the vehicle. Knob 24 is connected to shaft 28, which may be either a rod or a flexible shaft in case of need. Shaft 28 is pivoted at 29 to a link 30 which is pivoted at 31 to rockable arm 32, which arm is in fixed relation to the pintle 33 on which valve 21 is pivoted.

After the engine has been started, knob 24 will be pulled out, which will open valve 22 and permit the flow of hot air through inlet 85 9 with steam from stud 5 through outlet 11 through coupling 22 and pipe connection 10 to the intake manifold and the cylinders of the engine.

Having thus described this invention, I hereby point out that many minor changes may be made therein without departing from the spirit of this invention and the scope of the following claims.

I claim:

1. In a device of the character described, the combination of a casing having a bore therethrough of different diameters, a valve seat at the juncture of two diameters, an exit port for said bore through the wall of the casing connected with a manifold, a valve controlling the said outlet, an air inlet port, a plunger valve slidably mounted in the said bore adapted to close the said ports and seat on said valve seat, an elongated stud connected to and extending from said plunger valve into the said bore and beyond the valve seat with a loose fit therein, whereby a film of fluid may pass through the said bore around the stud when the plunger valve is moved off its seat, means for controlling the outlet valve, and means for operating the plunger valve.

2. In a device of the character described, the combination of a casing having a bore therethrough, of different diameters, a valve seat at the juncture of two diameters, an exit port for said bore through the wall of the casing connected with a manifold, a valve controlling the said outlet, an air inlet port, a plunger valve slidably mounted in said bore adapted to close the said ports and seat on said valve seat, an elongated stud connected to and extending from the said plunger valve into the said bore and beyond the valve seat with a loose fit therein, whereby a film of fluid may pass through said bore around the stud when the plunger valve is off its seat, a bracket on said casing, a lever fulcrumed in said bracket and pivot-

ally connected at one end to said plunger valve, and means to operate the said lever, and means to operate the said outlet valve.

3. In a device of the character described, 5 the combination of a casing having a chamber therein, an elongated bore extending axially through one end of the casing and of less diameter than and communicating with the said chamber, a valve seat at the 10 juncture of the chamber and the said bore, a hollow nipple extending from one end of the casing axially in alinement with and constituting a continuation of said bore, an 15 exit port for said chamber through the wall of the casing connected with a manifold, a valve controlling the said exit, an air inlet

port for said chamber, a plunger valve slidably mounted in the said chamber adapted to close the said ports and seat on said valve seat, an elongated stud connected to 20 and extending from said plunger valve and extending through the said bore with a loose fit therein whereby a film of fluid may pass through said bore around the stud, a bracket on said casing, a lever fulcrumed in said 25 bracket and pivotally connected at one end to said plunger valve, and means to operate the said lever, and means to operate the said outlet valve.

In testimony whereof I hereunto affix my 30 signature.

HARRY E. MAY.
